UNITED STATES PATENT OFFICE.

FRANK J. BEGER, OF HUDSON FALLS, NEW YORK, ASSIGNOR TO STANDARD WALL PAPER COMPANY, A CORPORATION OF NEW YORK.

DESIGN FOR WALL PAPER.

Application filed December 11, 1924. Serial No. 11,669. Term of patent 3½ years.

To all whom it may concern:

Be it known that I, FRANK J. BEGER, a citizen of the United States of America, and resident of Hudson Falls, in the county of Washington and State of New York, have invented a new, original, and ornamental Design for Wall Paper, of which the following is a specification.

Reference is had to the accompanying drawing in which the figure is a face view of a section of wall paper embodying the design.

I claim:

The ornamental design for wall paper as shown.

FRANK J. BEGER.
